United States Patent Office.

HERRMAN HEMPEL, OF NEW YORK, N. Y.

Letters Patent No. 65,671, dated June 11, 1867.

IMPROVEMENT IN BUTTON-HOLE CUTTERS.

The Schedule referred to in these Letters Patent and making part of the same.

TO ALL WHOM IT MAY CONCERN:

Be it known that I, HERRMAN HEMPEL, of the city, county, and State of New York, have invented a new and improved Button-Hole Cutter; and I do hereby declare that the following is a full, clear, and exact description thereof, which will enable others skilled in the art to make and use the same, reference being had to the accompanying drawings, forming a part of this specification, in which—

Figure 1 is a side view of my improved button-hole cutter.

Figure 2 is a cross-section of the same, taken on the line *x x*, fig. 1.

Figure 3 is a detail side view of the sliding rest; and

Figure 4 is a detail edge view of the cutter or knife.

Similar letters of reference indicate corresponding parts.

The invention relates to a new device for cutting button-holes of different lengths.

The improvements consist in having a sliding rest which is adjusted under the knife, so as to make the same cut longer or shorter holes; and also in making the knife in one piece, whereby it cannot only be made cheaper, but also easier fastened in the jaw or arm to which it is secured.

A and B are two arms, which are pivoted together like the arms of a common pair of shears; *a* and *b* are their respective handle ends; and *c* and *d*, their jaw ends, as shown in fig. 1. To the jaw *c* is secured the knife or cutter *C*, which is made so as to cut the eye and slit of a button-hole. Usually the knives for cutting button-holes are made of two pieces, the piece *e* for cutting the eye, and the long straight piece *f* for cutting the slit of the button-hole. It was very difficult to accurately secure these two pieces in the jaw, and when secured, they would easily get out of order. By making the whole knife in one piece, I can much easier adjust and secure it in the jaw *c*, providing simply a mortise in the inner surface of the jaw, and keeping the latter in position by means of wedges, set-screws, or other suitable devices. On the jaw *d* is arranged a sliding block, *D*, which when, in the position shown in fig. 1, is exactly under the knife *C*, and a button-hole can be then cut, which is as long as the whole knife. By moving the block *D* towards the pivot of the jaws a less portion of it will be brought under the cutting edge, and a shorter hole will be cut on it, and it can be so regulated that holes of any desired length, but none longer than the knife, can be cut on this machine. The block *D* is held on the jaw *d* by means of straps *g g* fitting around the jaw, as seen in figs. 1, 2, and 3. One of the sides of the jaw is provided with a row of small holes, as shown in fig. 3, into which a spring-catch, *h*, fits, so that thereby the block *D* can be firmly held in any desired position.

I claim as new, and desire to secure by Letters Patent—

The sliding block *D* when secured to the jaw *d* by means of straps *g g*, and when held in position by a spring-catch, *h*, fitting into one of a series of holes arranged on one side of the jaw *d*, all as set forth.

HERRMAN HEMPEL.
